Primary Examiner — Rhea Shields(57) **CLAIM**

The ornamental design for a biopsy system console, as shown and described.

DESCRIPTION

FIG. 1 is a perspective view of a biopsy system console showing the new design;

FIG. 2 is a front view of the biopsy system console of FIG. 1, with the cover in the closed position;

FIG. 3 is a front view of the biopsy system console of FIG. 1, with the cover in an open position;

FIG. 4 is a left side view of the biopsy system console of FIG. 1;

FIG. 5 is a right side view of the biopsy system console of FIG. 1; and,

FIG. 6 is a rear view of the biopsy system console of FIG. 1.

In the drawings, the broken lines are for the purpose of illustrating environment only and form no part of the claimed design.
